UNITED STATES PATENT OFFICE.

CHARLES AMES ALDEN, OF STEELTON, PENNSYLVANIA.

PROCESS OF MAKING RAILROAD FROGS AND PRODUCT THEREOF.

Application filed May 25, 1920. Serial No. 384,237.

To all whom it may concern:

Be it known that I, CHARLES AMES ALDEN, a citizen of the United States, and residing at Steelton, Dauphin County, State of Pennsylvania, have invented certain new and useful Improvements in Processes of Making Railroad Frogs and Products Thereof, of which the following is a specification.

The present invention relates to methods 10 of making railroad frogs and product thereof and more particularly to the production of such frogs from rolled, pressed or forged blanks as distinguished from castings.

The principal objects of the invention are 15 to increase production and at the same time lower the costs. Further objects consist in the provision of a frog which has a minimum number of parts and is inherently strong and capable of standing up under 20 all degrees of service.

To these ends the method of this invention consists in operating on a metal, preferably steel, bar of substantially uniform cross section to alter the shape at a 25 point adjacent where the wings are to end to provide for the flaring of the wings and increased width of the flange-ways at this point, and forming the flange-ways in the top of the bar to provide the wings and 30 point. If desired, the bar may be heat treated after the first operation.

Other objects and features of novelty will be apparent from the description taken in connection with the drawings in which:

35 Figure 1 is a top plan view of a bar or blank which is to be worked up into a finished frog;

Figure 2 is a sectional elevation of the bar taken on the line 2—2 of Figure 1;

40 Figure 3 is a top plan view of the bar or blank after the first operation has been performed thereon;

Figure 4 is a cross sectional elevation taken substantially on the line 4—4 of Figure 45 ure 3;

Figure 5 is a sectional elevation taken substantially on the line 5—5 of Figure 3;

Figure 6 is a top plan view of a frog finished from the blank of Figure 3;

50 Figure 7 is a sectional elevation taken substantially on the line 7—7 of Figure 6;

Figure 8 is a sectional elevation taken substantially on the line 8—8 of Figure 6;

55 Figure 9 is a sectional elevation taken substantially on the line 9—9 of Figure 6;

Figure 10 is a sectional elevation taken substantially on the line 10—10 of Figure 6.

Figure 11 is a sectional elevation taken substantially on the line 11—11 of Figure 6; 60

Figure 12 is a perspective view of a frog shown in Figure 6;

Figure 13 is a top plan view of an end portion of a frog showing a slight modification; 65

Figure 14 is a view similar to Figure 13 showing another modification;

Figure 15 is a sectional view taken substantially on the line 15—15 of Figure 14;

Figure 16 is a sectional elevation taken 70 substantially on the line 16—16 of Figure 14;

Figure 17 is a top plan view of a blank like that shown in Figure 1 after the first operation in the production of a modified 75 form of frog;

Figure 18 is a sectional elevation taken substantially on the line 18—18 of Figure 17;

Figure 19 is a sectional elevation taken 80 substantially on the line 19—19 of Figure 17;

Figure 20 is a sectional elevation taken substantially on the line 20—20 of Figure 17; 85

Figure 21 is a top plan view of a modified form of frog made from the bar or work shown in Figure 17;

Figure 22 is a sectional elevation taken substantially on the line 22—22 of Figure 21; 90

Figure 23 is a sectional elevation taken substantially on the line 23—23 of Figure 21;

Figure 24 is a sectional elevation taken 95 substantially on the line 24—24 of Figure 21;

Figure 25 is a sectional elevation taken substantially on the line 25—25 of Figure 21; 100

Figure 26 shows a blank or bar used in the manufacture of another form of frog;

Figure 27 is a sectional view of this bar;

Figure 28 illustrates the bar or blank after the first operations; 105

Figure 29 is a sectional view taken substantially on the line 29—29 of Figure 28;

Figure 30 is a sectional elevation taken substantially on the line 30—30 of Figure 28; 110

Figure 31 is a sectional elevation taken substantially on the line 31—31 of Figure 28;

Figure 32 is a top plan view of a frog constructed from the work or bar shown in Figure 28;

Figure 33 is a sectional elevation taken substantially on the line 33—33 of Figure 32;

10 Figure 34 is a sectional elevation taken substantially on the line 34—34 of Figure 32;

Figure 35 is a sectional elevation taken substantially on the line 35—35 of Figure 32;

15 Figure 36 is a sectional elevation taken substantially on the line 36—36 of Figure 32;

Figure 37 is a sectional elevation taken 20 substantially on the line 37—37 of Figure 32; and

Figure 38 is a sectional elevation taken substantially on the line 38—38 of Figure 32.

25 According to the present invention the frog is constructed from a rolled, pressed, or forged blank or bar, of substantially uniform cross section. Thus one form of bar which may be used is illustrated in Figures 1 and 2. As shown, this bar or blank 40 is of substantially uniform width and height throughout its length. In this form it is also of substantially uniform cross sectional area and shape throughout its length. 30 Preferably, the bar is substantially U-shape, having a longitudinally extending recess or groove 41 opening from its bottom face. At the lower edges of the longitudinal side faces the blank may be provided with oppositely extending base flanges 42, the bottom surfaces of which are flush with the bottom of the bar. This bar may be worked up into a plurality of forms of frogs, such as shown in Figures 6, 12, 13, 14 and 21. For 35 making a frog like that shown in Figures 6 and 12, the first step consists in operating on the bar of Figure 1 to alter the cross sectional shape at a point intermediate the ends of the bar. This operation is for the purpose of providing for the flaring of the wings at their ends and the increased width of the flange-ways adjacent the ends of the wings. As shown in Figure 3, this operation consists in forming the two recesses 43 40 substantially triangular in plan view and spaced transversely of the top of the bar and further in forcing out the outer walls 44 bounding these recesses so that the bar is widened at this point. This may be accomplished by indenting the bar as by a rolling, hammering, or pressing operation. The groove 41 at this region may simultaneously be widened and made deeper as shown by the cross sectional view, Figure 9. If desired, the work may be subjected to a suit-

able heat treatment at this stage of the process such as heating, quenching, reheating and cooling, for the purpose of increasing the elastic limit and ultimate strength of the steel, or change other properties. It will 70 be observed that the cross sectional area on the line 5—5 is substantially the same as the original cross sectional area of the blank, the shape only having been changed. Preferably at the same time that the cross sectional shape of the blank is altered at the desired point, the flanges 42 adjacent the ends of the bar may be offset toward the top of the bar a little, as indicated at 45, for a purpose presently to be described.

75 The next step in the method consists in operating on the top of the bar to form the flange-ways 46 and 47, these flange-ways including the recesses 43. Preferably, the flange-ways are formed by removing the metal from the top of the bar as by machining, thus providing the opposite wings 48 and 49 corresponding to the wing rails of a frog, and also providing the point 60 corresponding to the point rails. It will be noted 80 that the ends of the wings are flared outwardly as indicated at 50 and 51, and that the flange-ways adjacent thereto are thus widened.

85 For the purpose of providing means for securing the track rails to the frog a recess is made in each end thereof thus forming the projections or splicing members 52, 53 at one end of the bar and 54, 55 at the other. As previously explained, the flanges 42 are 90 offset upwardly at the ends of the frog, the object being to permit the projections at the ends of the frog to properly fit against the web of the track rails, as shown in Figures 7 and 11. For this purpose, it will be noted 95 that the tops of the projections are cut away and beveled to fit under the heads of the rails. A spreader piece 56 which is separable from the frog is interposed between the track rails at one end of the frog and a similar piece 57 is disposed at the opposite end. The track rails are secured in position by means such as the bolts 58 which extend 100 through the projections, the ends of the track rails, and the separator piece. The overall width of the frog at the ends is 105 substantially the same as that of the original blank and hence the end projections or splicing members 52, 53, 54 and 55, are slightly tapered as shown, whereby the track 110 rails take the proper directions relative to the frog.

115 Figure 13 shows a slight modification in which the end projections or splicing members 152 and 153 are not tapered but are of the same width throughout their length. In order to accommodate the track rails therefore these projections or splicing members are slightly flared or bent apart, a suitable separating block, as indicated at 156 120

being provided, and all the parts being secured together as by the bolts 58. It is to be understood that a similar structure may be employed at the other end of the frog.

5 Figures 14, 15 and 16 show another modification of the structure at the ends of the frog. In this case the structure is the same as that shown in Figures 6 and 12 except that part of the separator between the track 10 rails consists of a projection 256 integral with the frog. This projection is of a thickness substantially equal to the distance between the top of the groove 41 and the bottom of the flange recess in the frog, and 15 shaped at its sides to fit against the track rails as shown in Figure 15. The remainder of the separator is formed by a separable piece 256 disposed under the integral piece 256. The parts are held together by the 20 bolts 58.

Another form of frog is illustrated in Figure 21 and this frog may be made from the blank shown in Figure 1 by operating on the same to form the work or bar shown 25 in Figure 17. The blank has been operated on in any suitable way as by a rolling, pressing or hammering operation to change the cross sectional shape of the bar at two points. At one point, as indicated by the 30 cross sectional view of Figure 19, the top of the bar is widened in the same way as described in connection with Figure 3. Adjacent this section 19—19 such as at a section 20—20, the bar has been narrowed and 35 its height slightly increased, the cross sectional area however, remaining substantially the same. After this operation the bar or work may be subjected to a suitable heat treatment.

40 Next, the work of Figure 17 is operated upon to form flange-ways 346 and 347 as by machining and thus provide wings 348 and 349 and the point 360, the ends of the wings being flared as at 350 and 351. The added 45 height shown in Figure 20, due to narrowing the bar is removed by machining or otherwise to give a flat top surface on the point.

For securing the track rails to the frog, 50 separable splice plates 352 and 353 are employed at one end and 354 and 355 at the other. The sides of the frog at its ends are machined out to take the splice plates as indicated at 370 and 371, Figure 23, and 372 55 and 373, Figure 24. Interposed between the track rails are separating members at the ends of the frog of suitable shape to hold the rails properly diverging, each of which consists of an integral part as 356 or 357, 60 and a separable lower part 356' or 357'. The rails are secured to the ends of the frog and the parts fastened together by the bolts 58. The splice plates 352 and 353 are slightly bent, as shown in Figure 21, where-

as the splice plates 354 and 355 at the other 65 end of the frog are straight. The base flanges are removed at the ends of the bar to a point inside of the recesses 370 and 371.

In another modified form of the invention the frog may be formed from a solid 70 bar of uniform cross section such as indicated at 440, Figure 26, this bar having the base flanges 442. The first operation consists in forming the recess or groove 441 in the bottom of the blank, this groove having 75 different widths, as indicated in the plan view 28 and sectional views Figures 29, 30 and 31. The blank is not widened, except at the region where the wings end, as indicated by the section of Figure 31. The central part of the groove may be made deeper at this section. After these operations, which slightly elongate the bar, the same may be subjected to a suitable heat treatment. Thereafter the top of the bar is 80 formed with flange-ways 446 and 447, thus providing the wings 448 and 449 and the point 460. These flange-ways may be formed by removing the metal as by machining. 85

The track rails are secured to the frog at one end by the integral separator block 456, removable bent splice plates 452, 453 and bolts 58. At the other end the track rails are secured to the frog by the integral 90 separator block 457, straight removable splice plates 454 and 455 and bolts 58. As shown in Figures 33 and 38, the integral separator blocks 456 and 457 are properly 95 shaped to fit against the webs of the rails 100 between the base flanges and heads thereof. The sides of the bar adjacent the base of the separator blocks or extensions are channeled or recessed to receive the splice plates. Thus at one end the sides are formed with 105 the recesses 470 and 471 for the splice plates 452 and 453 and at the other end the sides are formed with the recesses 472 and 473 for the splice plates 454 and 455. The base flanges 442 at the first mentioned end of 110 the bar are cut away or removed for a length substantially the same as said recesses 470 and 471 and are narrowed at the other end. Further at the first mentioned end the top 115 of the bar is formed with the lateral cut away parts 474 and 475 so that the shoulders thus formed constitute smooth extensions of the outside surfaces of the heads of the track rails.

The modification of the method illustrated 120 by Figures 26 to 38 inclusive is claimed in a separate application, Serial Number 384,238.

The term "worked" as used in the claims, is intended to cover blanks produced by 125 working the metal as by forging, rolling, or pressing, to distinguish from cast blanks.

Although embodiments of the invention

4
have been described in detail, it is to be understood that the invention is not thus limited but includes modifications and changes which come within the scope of the appended claims.

Having thus described the invention what is claimed as new and desired to be secured by Letters Patent is:

1. The process of making railroad frogs 10 consisting in operating on a worked metal blank of substantially uniform cross sectional shape to widen the same approximately at a point where the wings are to end, and removing metal from the top of the bar to form the flange-ways, wings and point.
2. The process of making railroad frogs 20 consisting in operating on a worked metal bar of substantially uniform cross sectional shape to widen the same without substantially altering its height approximately at a point where the wings are to end, and removing metal from the top of the bar to form the flange-ways, wings and point.
3. The process of making railroad frogs 25 consisting in operating on a worked metal bar of substantially uniform cross sectional shape to widen the same at the top thereof approximately at a point where the wings are to end, and removing metal from the top of the bar to form the flange-ways, wings and point.
4. The process of making railroad frogs 35 consisting in operating on a worked metal bar of substantially uniform cross sectional shape to widen the same approximately at a point where the wings are to end, removing metal from the top of the bar to form the flange-ways, wings and point and forming projections at the ends of the bar adapted to connect the track rails to the frog.
5. The process of making railroad frogs 45 consisting in operating on a blank of substantially uniform cross sectional shape to widen the same approximately at a point where the wings are to end and forming flange-ways in the top of the bar to provide the wings and point.
6. The process of making railroad frogs 50 consisting in operating on a steel bar of substantially uniform cross sectional shape to widen the same approximately at the point where the wings are to end, and machining out flange-ways in the top of the bar thereby forming the wings and point.
7. The process of making railroad frogs 55 consisting in operating on a worked metal bar of substantially uniform cross sectional shape to form two transversely spaced recesses adjacent the point where the wings are to end and forcing out the outer walls bounding said recesses to widen the bar, and forming flange-ways including said recesses to provide the wings and point of the frog.

8. The process of making railroad frogs 65 consisting in operating on a worked metal bar of substantially uniform cross sectional shape to form two transversely spaced recesses adjacent the point where the wings are to end and forcing out the outer walls bounding 70 said recesses to widen the bar, and removing metal from the top of the bar to form the flange-ways including said recesses, to provide the wings and point of the frog.

9. The process of making railroad frogs 75 consisting in operating on a metal bar of substantially uniform cross sectional shape to form two transversely spaced recesses adjacent the point where the wings are to end and forcing out the outer walls bounding 80 said recesses to widen the bar, and machining out flange-ways in the top of the bar including said recesses, thereby forming the wings and point of the frog.

10. The process of making railroad frogs 85 consisting in operating on a bar of substantially uniform cross sectional shape having a longitudinal groove in the bottom thereof, to increase its width and decrease the thickness of metal over said groove at 90 a point adjacent where the wings are to end, and forming flange-ways in the top of the bar to provide the wings and point.

11. The process of making railroad frogs 95 consisting in operating on a steel bar having uniform width and height throughout its length to make the bar wider at the top thereof adjacent the point where the wings are to end, and forming flange-ways to provide the wings and point.

12. The process of making railroad frogs 100 consisting in operating on a bar having uniform width and height throughout its length to make the bar wider at the top thereof adjacent the point where the wings are to end, 105 forming the flange-ways to provide the wings and point, and forming integral projections at the ends of the bar for securing the track rails to the frog.

13. The process of making railroad frogs 110 consisting in forming two transversely spaced recesses in the top of a bar having substantially uniform width and height, forcing out the outer walls bounding said recesses, and forming flange-ways including 115 said recesses to provide the wings and point.

14. The process of making railroad frogs 120 consisting in indenting two transversely spaced recesses in the top of a bar having substantially uniform width and height thereby forcing out the outer walls bounding 125 said recesses, and forming flange-ways including said recesses to provide the wings and point.

15. The process of making railroad frogs 125 consisting in operating on a steel bar of substantially uniform width and height to alter the cross sectional shape at a point adjacent

where the wings are to end, heat treating the bar and forming flange-ways in the top of the bar to provide the wings and point.

16. The process of making railroad frogs consisting in forming two transversely spaced recesses in the top of a steel bar having substantially uniform width and height, forcing out the outer walls bounding said recesses, heat treating the bar, and forming flange-ways including said recesses to provide the wings and point.

17. The process of making railroad frogs consisting in operating on a steel bar of substantially uniform cross sectional area to widen the same approximately at a point where the wings are to end, heat treating the bar and forming flange-ways in the top of the bar to provide the wings and point.

18. The process of making railroad frogs consisting in operating on a steel bar of substantially uniform width and height to alter the cross sectional shape at a point adjacent where the wings are to end, heat treating the bar and machining out flange-ways in the top of the bar to provide the wings and point.

19. The process of making railroad frogs consisting in operating on a metal bar of substantially uniform width and height, to displace the metal in the top at the side edges laterally at the region where the wings are to end, to form the flaring ends of the wings, and forming the flange-ways to provide the wings and point.

20. The process of making railroad frogs consisting in operating on a metal bar of substantially uniform cross sectional shape having base flanges to increase its width at the region where the wings are to end, offsetting the flanges upward at the end portions of the bar an amount equal to the thickness of the base flange of the track rails, and removing metal from the top of the bar to form the flange-ways, wings and point.

21. The process of making railroad frogs consisting in operating on a metal bar of substantially uniform cross sectional shape having base flanges to increase its width at the region where the wings are to end, offsetting the flanges upward at the end portion of the bar an amount equal to the thickness of the base flange of the track rails, removing metal from the top of the bar to form the flange-ways, wings and point and forming a recess in an end of the bar to provide integral splice plates for securing the track rails to the frog.

22. The process of making railroad frogs consisting in operating on a metal bar of substantially uniform cross sectional shape having base flanges to increase its width at the region where the wings are to end, removing metal from the top of the bar to form the flange-ways, wings and point and

forming two integral spaced splice plates at an end of the bar for securing the track rails to the frog.

23. The process of making a railroad frog consisting in operating on a metal bar of substantially uniform cross sectional area having base flanges and a longitudinal groove in its base, to widen the bar and decrease the thickness of metal between the top of the groove and the top of the bar adjacent the region where the wings are to end, removing metal from the top of the bar to form the flange-ways, wings and point and forming integral splice plates at an end of the bar for securing the track rails to the frog.

24. The process of making railroad frogs consisting in operating on the top and bottom of a bar, of substantially uniform cross sectional shape, at the region where the wings are to end, to widen the same, and removing stock from the top of the bar to form the flange-ways, wings and point.

25. The process of making railroad frogs consisting in indenting the top of a bar of substantially uniform cross sectional shape, at the region where the wings are to end, to widen the same, and removing stock to form the flange-ways, wings and point.

26. The process of making railroad frogs consisting in indenting the top and bottom of a bar of substantially uniform cross sectional shape, at the region where the wings are to end, to widen the same, and removing stock to form the flange-ways, wings and point.

27. As an article of manufacture, a single-piece worked metal railroad frog of substantially uniform cross sectional area throughout the greater part of its length.

28. As an article of manufacture, a railroad frog made from a bar of worked metal of substantially uniform cross section, the finished frog being of the same length as the bar.

29. As an article of manufacture, a single-piece railroad frog made from a bar of worked metal of substantially uniform cross section, the finished frog being of the same length as the bar and substantially of the same cross sectional area.

30. A blank adapted to be made into a one piece railroad frog comprising a bar of rolled metal of uniform cross sectional shape, said bar having base flanges and a longitudinally extending groove in its bottom face.

31. As an article of manufacture, a non-cast, one-piece frog having a point, wings and flange-ways, said frog formed from a bar of worked metal of uniform cross sectional shape.

In testimony whereof I affix my signature.
CHARLES AMES ALDEN.
